REMOVAL OF WAX FROM HYDROCARBON
OILErnest F. Pevere, Beacon, N. Y., assignor to The
Texas Company, New York, N. Y., a corporation
of Delaware

Application May 25, 1934, Serial No. 727,385

11 Claims. (Cl. 196—19)

This invention relates to the dewaxing of wax bearing oil, and particularly to the separation of wax from a mineral lubricating oil.

The invention contemplates the separation of 5 wax from such a wax bearing oil by the employment of an organic ester as a wax crystal modifying material, to facilitate dewaxing by centrifuging, cold settling or filtration. In accordance with the present invention, the wax crystal 10 modifying material is added to a wax bearing oil, and the oil then chilled with resultant precipitation of wax in a form which is found to facilitate separation by centrifuging or cold settling, and which is also found to materially increase 15 filtering rates where the wax is separated by filtration.

Various types of organic esters are suitable for 20 purposes of the present invention. For example, glycerol esters of fatty acids, and particularly 25 the higher saturated fatty acids, such as glycerol tristearate, glycerol tripalmitate, etc., constitute highly effective wax crystal modifying materials. The glycerol mono- and di- esters of these fatty 30 acids may also be employed, where the solubility characteristics of the esters in the particular oil 35 being treated permits the solution of a sufficient quantity, such for example as 0.5% to about 5.0% or more by weight.

The various glycol esters of fatty acids, and 40 particularly the higher saturated fatty acids, are also very satisfactory for purposes of the present invention. For example, ethylene glycol distearate, ethylene glycol dipalmitate, and the corresponding mono-esters of ethylene glycol, are very 45 satisfactory.

Fatty acid esters of polyhydric alcohols higher 50 than glycerol, such as the tetrahydric alcohol erythritol, and the hexahydric alcohols, such as mannitol and sorbitol, are also satisfactory. For 55 example, mannitan tetrastearate is found to be highly effective.

Fatty acid esters of higher molecular weight 60 monohydric alcohols having 6 or more carbon atoms to the molecule, such for example as hexyl, heptyl, octyl and cetyl alcohols, may likewise be 65 employed. Cetyl stearate is an example of an effective ester of this class.

In addition to the fatty acid esters mentioned 70 above, the esters formed from the above-mentioned alcohols with acids derived from oxidized 75 paraffin wax, or other waxy hydrocarbons, may also be employed.

An ester, or mixture of esters, from the classes 80 mentioned above, may be employed in minor proportions with a wax bearing oil to be treated. In general, it may be stated that a proportion of from about 0.5% to 10% by weight may be used. However, the beneficial effect of the ester addition 85 generally increases with an increase in proportion up to a certain definite amount; and

further addition then may produce no additional beneficial effect, and in fact may decrease the effectiveness. The most advantageous proportion can be readily determined by tests with the particular ester and the particular wax bearing oil employed. 5

The organic ester of the character described above is preferably employed in conjunction with a dewaxing solvent or solvent mixture. Various solvents can be used for this purpose, such for example as acetone, ethylene dichloride, methyl 10 ethyl ketone, naphtha, various aliphatic alcohols and the like. Very satisfactory results are secured by the use of a mixture of a wax solvent with a non-solvent, such as a mixture of benzol 15 and acetone, for instance in the proportions of 65% benzol to 35% acetone. Another very satisfactory solvent mixture of this character, particularly for use in the dewaxing of residual oils, 20 consists of 28-35% acetone, 47-57% benzol and 15-18% toluol. A comminuted filter aid material of the character of infusorial or diatomaceous earth may also be employed in conjunction with the wax crystal modifying material, and also with the solvent or solvent mixture. The filter 25 aid material may be added prior to, during or after chilling.

By way of example, the invention is hereinafter particularly described and illustrated in the accompanying drawing, in which the single figure 30 is a flow sheet of the method, wherein glycerol tristearate is prepared and utilized as a dewaxing aid. As shown, glycerine and commercial stearic acid from supply tanks 10 and 11 respectively, are supplied to an esterification vessel 12, 35 where the ester is formed in conventional manner, such as that suggested by Bellucci (Journal of the Chemical Society, Abstracts, 1911, Volume I, page 416). Ether is added from tank 13 to form a solution of the reaction product, and the 40 solution passed to washing tank 14, where it is washed with weak caustic solution and then with distilled water from suitable sources of supply 45 15 and 16, to remove free fatty acids. The washed solution is then distilled in still 17 to 45 remove the ether which is condensed in condenser 18 and returned to storage 13 for reuse. The purified glycerol ester is passed to storage 18'.

The wax crystal modifying material is added 50 from tank 18 to a wax bearing oil from storage 19 in a suitable mixer and agitator 20. The proportions in which the modifying material can be added to the wax bearing oil vary within substantial limits; but it is found that by increasing the proportion up to a certain amount for a particular oil gives increasingly beneficial effect, 55 while increasing the proportion beyond that amount gives no further benefit, and in fact, may decrease the effectiveness. For example, a proportion of from 1% to 5% by weight of the glyc- 60

erol ester material prepared as outlined above, generally provides satisfactory results. The glycerol ester may be added directly to the lubricating oil in which it is readily soluble; or a solution of the ester may be first prepared in a suitable solvent, such as a lubricating oil or a dewaxing solvent, and the solution added to the wax bearing oil to give the desired proportion of ester in the mixture.

10 A dewaxing solvent from storage tank 22 is preferably added to the wax bearing oil. By way of example, a solvent mixture of 35% acetone and 65% benzol in the proportions of 1 part of oil to 3 parts of acetone-benzol mixture is herein described. The oil mixture is then passed through chilling coils 23 where it is chilled to a temperature of around 0° to -10° F. A filter aid material from the hopper feed 24 may be supplied by line 25 to the agitator 20, so that the oil is chilled in the presence of the filter aid material. Or, the filter aid material can be supplied by line 26 to the already chilled oil as the latter is fed to a filter 27. Or, a proportion of filter aid can be added both before and after chilling. The filter 27 may be of any suitable conventional construction, such for example, as a pressure filter or a continuous filter. The solids including wax are removed by the filter and passed to a receiving vat 28, while the filtrate of dewaxed oil and solvent passes to a solvent recovery still 29. Here, the solvent is distilled from the dewaxed oil, and passed to a receiving tank 30, from which it may be returned to the storage tank 22 for reuse in the process. The dewaxed oil is accumulated in a receiving tank 31.

Where a solvent mixture of the character of acetone-benzol or acetone-benzol-toluol is employed, the resulting wax free oil is found to have a pour test of around 0° F. when chilled only to about 0° F. or slightly below. The filtering rates of the chilled oil may be improved as much as 100% to 150% above those obtained when a similar chilled mixture omitting the wax crystal modifying material, is employed. Where 45 the wax bearing oil mixtures containing the wax crystal modifying material is chilled to about -10° F. and subjected to cold settling, it is found that more rapid settling of the solid constituents occurs, and a clear supernatant liquid layer of oil 50 and solvent may be readily drawn off from the settled solids. When the solvent is then removed by distillation, a substantially wax free oil of low pour test of around 0° F. is obtained. Where the chilled mixture containing the wax crystal modifying material is subjected to centrifuging, improved separation of the wax from the oil results, giving a wax-free oil of the desired low pour test.

60 As a further example, ethylene glycol distearate may be prepared from commercial stearic acid by reacting ethylene chloride with the potassium salt of stearic acid according to the following equation:

70 The resulting product may then be purified by dissolving in ether, washing the ethereal solution first with weak sodium hydroxide solution and then with distilled water, and finally evaporating

the ether to obtain the ester as a white solid. The ester is then added to a wax bearing oil, preferably in the proportion of about 1% to 5% by weight, together with a dewaxing solvent or solvent mixture of the character described above. 5 The oil mixture is then chilled to cause precipitation of the wax, and the wax then separated in the manner previously described.

When in the claims I use the words "fatty acid", I refer to the aliphatic acids generally obtained 10 from commercial fats and oils. It is understood that I do not refer to acetic acid and its immediate homologs.

Obviously many modifications and variations of the invention, as hereinbefore set forth, may 15 be made without departing from the spirit and scope thereof, and therefore only such limitations should be imposed as are indicated in the appended claims.

I claim:

1. The method of dewaxing a wax bearing oil, which comprises mixing with the oil an organic ester which has the property of modifying wax crystal formation upon chilling of the oil in the presence thereof, the said ester being selected 25 from the group consisting of fatty acid esters of glycerol, fatty acid esters of glycols, fatty acid esters of monohydric alcohols selected from the group consisting of hexyl, heptyl, octyl and cetyl alcohols, fatty acid esters of polyhydric alcohols 30 of the series higher than glycerol selected from the group consisting of erythritol, mannitol and sorbitol, and esters of the above-mentioned alcohols with the acids derived from oxidized waxy hydrocarbons, chilling the mixture to precipitate 35 the wax, and separating the wax from the oil.

2. The method of claim 1, in which the ester is a glycerol ester of a saturated fatty acid.

3. The method of claim 1, in which the ester is glycerol tristearate.

4. The method of claim 1, in which the ester is a glycol ester of a saturated fatty acid.

5. The method of claim 1, in which the ester is ethylene glycol distearate.

6. The method of claim 1, in which the ester is 45 a hexahydric alcohol ester of a saturated fatty acid.

7. The method of claim 1, in which the ester is mannitan tetrastearate.

8. The method of claim 1, in which the wax 50 is separated from the oil by filtration, and in which the ester serves to materially increase the filtration rate.

9. The method of claim 1, in which a dewaxing solvent is also added to the wax bearing oil prior 55 to wax separation, the solvent being of such character that the normally liquid and normally solid constituents of the oil are soluble therein at elevated temperatures of the order of 100° F. and above, and the normally liquid constituents 60 are soluble while the normally solid constituents are substantially completely insoluble therein at lowered temperatures of the order of 0° F. and below.

10. The method of claim 1, in which a dewaxing solvent comprising acetone and benzol is added to the wax bearing oil prior to wax separation.

11. The method of claim 1, in which a filter aid material is added to the wax bearing oil 70 prior to wax separation.

ERNEST F. PEVERE.
